UNITED STATES PATENT OFFICE.

JOHN F. O'CONNOR, OF CHICAGO, ILLINOIS, ASSIGNOR TO WILLIAM H. MINER, OF CHAZY, NEW YORK.

HAND BRAKE.

1,403,188.

Specification of Letters Patent. Patented Jan. 10, 1922.

Application filed May 3, 1919. Serial No. 294,443.

To all whom it may concern:

Be it known that I, JOHN F. O'CONNOR, a citizen of the United States, residing at Chicago, in the county of Cook and State of Illinois, have invented a certain new and useful Improvement in Hand Brakes, of which the following is a full, clear, concise, and exact description, reference being had to the accompanying drawings, forming a part of this specification.

This invention relates to improvements in hand brakes for railway cars.

The object of the invention is to provide a simple relatively inexpensive hand brake especially adapted for railway cars and wherein an easily ratcheting action is permitted.

More specifically, the object of the invention is to provide a ratchet hand brake wherein the operating member is adapted to drop to an inoperative position under the influence of gravity.

In the drawing forming a part of this specification, Figure 1 is a vertical sectional view through a portion of a car wall showing my improvements in connection therewith. Fig. 2 is a horizontal sectional view taken substantially on line 2—2 of Fig. 1. Fig. 3 is a detailed view taken substantially on line 3—3 of Fig. 1.

In said drawing 10 denotes the end wall of a car, and 11 the vertical brake staff. The brake staff will have at its lower end its usual chain winding drum as will be understood and does not require illustration. The top end of the staff is preferably squared as indicated at 12, and over this squared section is slipped a cast ratchet wheel 13. As will be obvious the ratchet wheel 13 will rotate with the staff 11. At its lower end, the cast ratchet wheel 13 is provided with a cylindrical bearing sleeve 14 which rotates in a suitable bearing 15 provided in the bracket 16 that is preferably riveted to the car wall as indicated at 17. The upper end of the ratchet wheel 13 is provided with a similar bearing sleeve as indicated at 18, which is rotatably mounted in a corresponding bearing 19 provided by an upper bracket 20 also riveted to the wall of the car. The bracket 20 is provided with an upstanding preferably hollow extension 21 which forms a convenient member for the brakeman to grip while operating the brake.

The lower bracket 16 is provided with an

upstanding curved flange as indicated at 22 which forms a partial housing for the ratchet wheel 13. Mounted on the ratchet wheel itself and journaled about the bearing sleeve 18 thereof is a casing member 23 having a depending substantially circular flange 24 which is partially telescoped over the flange 22 and in conjunction with the latter conceals the ratchet wheel and protects it from the elements. The casing or housing 23 is also formed with radially extending flanges 25—25 united with a top wall 26 as shown most clearly in Fig. 3, the same forming a housing for the pawl and its mounting hereinafter explained.

The operating handle for the brake is designated generally by the reference A. The same has a handle proper 27 of suitable length and a single pawl tooth 28, shown most clearly in Fig. 2. The member A is 75 pivotally mounted on a rivet or pin 29 carried by a hanger 30 so that the member A may oscillate in a horizontal plane while in the full line position shown in Fig. 1 but will drop to the substantially vertical 80 position as shown by the dotted lines in Fig. 1, this being permitted because of the pivot provided by the bolt 32 which passes through depending flanges 31 of the member 30 and the flanges 25. When in the dotted 85 line position it is obvious that the pawl 28 is disengaged from the ratchet wheel 13 and release of the ratchet wheel (as hereinafter explained) cannot possibly cause any injury to the brakeman such as might occur were 90 the pawl engaged with the ratchet wheel during release.

To hold the ratchet wheel 13 and staff against reverse rotation during the winding movement, I provide a locking dog indicated 95 at 33, which co-operates with the lower part of the ratchet wheel 13. Said dog 33 is pivoted on the bolt 34 as shown in Fig. 1 and at its other ends it is provided with a handle 35 to effect its operation. To hold 100 the dog 33 normally in locking engagement with the ratchet wheel, I provide a spring 36 seated at one end over a stud 37 carried by the dog and at its other end over a stud 38 formed integrally with the bracket 16. 105

In order to assure retaining the pawl 28 in proper position during the winding movement, that is when the lever A is rotated in a counter-clockwise direction as shown in Fig. 2, the pawl 28 is preferably provided 110

with a shoulder 39 which engages the adjacent side wall of the hanger 30 as shown in Fig. 2. It is obvious that the shoulder 39 limits the oscillation of the lever A with respect to the hanger in one direction but does not interfere with the free oscillation of the lever 30 in the opposite direction with respect to the hanger 30.

I claim:

10. In a brake for railway cars, the combination with a vertical brake staff having a ratchet wheel rotatable in unison therewith; of a hanger loosely rotatably mounted with respect to said staff, a supporting member 15 mounted on said hanger to swing about an axis extending transversely of said staff, said supporting member having a flange extending radially from said axis; and a combined pawl and gravity drop handle pivotally mounted on said supporting member 20

to oscillate about an axis arranged at right angles to said first named axis, the pawl being adapted to co-operate with said ratchet wheel, and the combined pawl-handle having a laterally offset shoulder 25 adapted to engage with said flange of the supporting member when the handle is pulled in a direction to rotate the staff to apply the brake whereby the oscillation of said combined pawl-handle about said second named axis is limited with respect to said supporting member in applying the brake.

In witness that I claim the foregoing I have hereunto subscribed my name this 17 35 day of April, 1919.

JOHN F. O'CONNOR.

Witness:

CARRIE GAILING.
